ATTORNEY.

UNITED STATES PATENT OFFICE.

RUPERT N. OYSLER, OF DAVENPORT, IOWA.

WRENCH.

1,326,526.

Specification of Letters Patent. Patented Dec. 30, 1919.

Application filed September 6, 1919. Serial No. 322,111.

To all whom it may concern:

Be it known that I, RUPERT N. OYSLER, a citizen of the United States, residing at Davenport, in the county of Scott and State of Iowa, have invented certain new and useful Improvements in Wrenches, of which the following is a specification, reference being had to the accompanying drawings.

This invention relates to wrenches, and 10 has for its object to provide a device of this character, the handle of which revolves and includes at its ends a plurality of nut engaging sockets of various sizes which may be instantly adjusted.

15 Another object of this invention is to provide a novel mechanism for locking the sockets firmly in position when in use.

A still further object of the invention is to provide a wrench of this character having pivoted to its end a terret including a plurality of sockets which may be instantly rotated to bring the desired socket into position and then firmly lock it to the rotating handle.

25 These objects are attained by the mechanism illustrated in the accompanying drawing, in which:

Figure 1 is a perspective view of the complete wrench.

30 Fig. 2 is an end view of the terret.

Fig. 3 is a detail view of the spring and key for securing the terret to the handle.

Referring to the drawings, 5 indicates the shank of a handle, having its end portion 6 bent outwardly and upwardly and provided at its end with a knob 7 which is pivoted thereto. A hand grip 8 is carried by the shank 5 of the handle. The remaining end 9 of the handle is bent at right angles 35 to the shank 5 and is provided with a groove or keyway 10. A terret 11 is provided and includes a plurality of radiating nut engaging sockets 12. These sockets are of various sizes. The central portion of the terret 11 40 has a central bore 13, through which the end 9 of the handle extends. A washer 14 is disposed on the end of the handle, and retained by means of a screw to prevent disengagement of the terret from the handle.

45 Communicating with the bore 13 is a plurality of keyways 15. Slidably mounted in the keyway 10 is a key 16 provided with an operating finger piece 17 adapted to withdraw the key 16 from the keyways in the 50 terret 11 when it is desired to adjust the terret.

Encircling the key way and end 9 of the handle is an expansion spring 18 secured at one end to the handle and at its other end to the key 16 with the finger piece 17 and 60 is intended to urge the key outwardly from the end of the handle into the registering keyways 15 of the terret and to prevent disengagement of the key 16 from the keyway 10.

65 In operation, to bring the desired wrench engaging socket into position, the finger piece 17 is grasped by the operator so as to withdraw the key 16 from the keyway of the terret. The terret is then rotated to bring the 70 desired socket in position, whereupon the finger piece is released and the key, through the action of the spring, is forced into the registering keyway in the terret. During the operation of the wrench, the knob 7 is 75 held stationary while the handle 8 is grasped to revolve the handle and terret.

80 From the foregoing description, it will readily be seen that this wrench can be instantly adjusted to accommodate various sizes of nuts, and in view of its novel form of handle permits greater force to be applied to the nut in the tightening or loosening operation. It is particularly adapted for use on demountable automobile wheel 85 rims, and will also be found especially useful for the various parts of the engine. The various sizes of sockets, however, permit its unlimited utility wherever a wrench is desired.

85 What is claimed is:

1. In a wrench, a rotatable handle having a groove extending through one end thereof, a nut engaging member having a central bore, and a plurality of recesses communicating with the bore, said member being rotatable on the handle over a portion of the groove, and a key slidable in the groove and projecting above the surface of the handle, one end of the projecting portion engaging a registering recess of the bore to key said member to the handle.

90 2. In a wrench, a rotatable handle having a groove extending through one end thereof, a nut engaging member having a central bore, and a plurality of recesses communicating with the bore, said member being rotatable on the handle over a portion of the groove, and a key slidable in the groove and projecting above the surface of the handle, one end of the projecting portion engaging 95 a registering recess of the bore to key said member to the handle.

100 3. In a wrench, a rotatable handle having a groove extending through one end thereof, a nut engaging member having a central bore, and a plurality of recesses communicating with the bore, said member being rotatable on the handle over a portion of the groove, and a key slidable in the groove and projecting above the surface of the handle, one end of the projecting portion engaging 105 a registering recess of the bore to key said member to the handle.

member at its pivotal connection to the handle.

3. In a wrench, a rotatable handle having a groove extending through one end thereof, 5 a nut engaging member having a central bore and a plurality of recesses communicating with the bore, said member being rotatable on the handle over a portion of the groove, a key slideable in the groove and projecting above the surface of the handle, one 10 end of the projecting portion engaging a

registering recess of the bore, the opposite surface of the end portion engaging the groove within the bore and a spring secured at one end to the handle and surrounding 15 the grooved portion thereof and the key for operating and preventing disengaging of the key from the handle.

In testimony whereof I hereunto affix my signature.

RUPERT N. OYSLER
